US00D985567S

(12) **United States Design Patent** (10) **Patent No.:** **US D985,567 S**
(45) **Date of Patent:** **** May 9, 2023**

(54) **ERGONOMIC KEYBOARD**

(71) Applicant: **Cloud Nine Ergo LLC**, Boulder, CO (US)

(72) Inventor: **Blake Olson**, Superior, CO (US)

(73) Assignee: **CLOUD NINE ERGO LLC**, Boulder, CO (US)

(**) Term: **15 Years**

(21) Appl. No.: **29/771,612**

(22) Filed: **Feb. 24, 2021**

(51) LOC (14) Cl. **14-02**

(52) U.S. Cl.

USPC **D14/393**

(57) **CLAIM**

The ornamental design for an ergonomic keyboard, as shown and described.

DESCRIPTION

FIG. 1 is a top right perspective view of the ergonomic keyboard.

FIG. 2 is a top view thereof.

FIG. 3 is a bottom view thereof.

FIG. 4 is a left side view thereof.

FIG. 5 is a right-side view thereof.

FIG. 6 is a rear view thereof.

FIG. 7 is a front view thereof.

FIG. 8 is a bottom left perspective view thereof; and,
FIG. 9 is a bottom front perspective view thereof.

The broken lines illustrate portions of the article, whereas the dot-dash broken lines represent a boundary of the claimed design. None of the broken lines form any part of the claimed design.

1 Claim, 7 Drawing Sheets
